Primary Examiner — Cathron C Brooks*Assistant Examiner* — Kevin K Rudzinski(57) **CLAIM**

The ornamental design for an bucket for inspecting aviation fueling underwing nozzle, as shown and described.

DESCRIPTION

FIG. 1 is a left side elevation view showing the quality control bucket, the right side elevation view being a mirror image;

FIG. 2 is a back side elevation view;

FIG. 3 is a top plan view; and,

FIG. 4 is a front elevation view.

The broken lines shown in FIG. 1 show environmental structure not being claimed and the dash-dot-dash lines included in the drawings shows the bounds of the claimed design and form no part of the claimed design.
